US00D960971S

(12) United States Design Patent (10) Patent No.: US D960,971 S
Shin (45) Date of Patent: * Aug. 16, 2022

(54) WRITING PAPER

(71) Applicant: Noutecompany Co., Ltd., Seoul (KR)

(72) Inventor: Dong Hwan Shin, Seoul (KR)

() Term: 15 Years

(21) Appl. No.: 35/511,988

(22) Filed: Dec. 9, 2020

(80) Hague Agreement Data

Int. Filing Date: Dec. 9, 2020

Int. Reg. No.: DM/212267

Int. Reg. Date: Dec. 9, 2020

Int. Reg. Pub. Date: Jun. 11, 2021

(30) Foreign Application Priority Data

Nov. 2, 2020 (KR) 30-2020-0052413

(51) LOC (13) Cl. 19-01

(52) U.S. Cl.

USPC D19/1

(58) Field of Classification Search

USPC D19/1-11, 26, 31, 100
